Fig. 3.

The following is copied from the G. C. & G. Patent and making part of the same containing a description in the words of the said Royal Dove himself of a Machine for Shearing cloth.

This machine consists of an exterior frame which supports the acting machinery, several rollers which aid the progress of the cloth upon the shear, and wheels or wheels for communicating motion, a brush for raising the nap previous to its coming under the shear, a cushion which lifts the cloth to the level of the shear, a bed shear and a flying or moveable shear, the frame on which the latter hangs, and the crank axis or hand or arms which move the flying shear. In particular describing these several parts of the machine. I will use the natural order in which they succeed each other in the operation of shearing, so far as is practicable and consistent with brevity. The exterior frame is constructed of wood or other proper material, elevated on feet high enough to allow space for the revolution of the wheels or wheels used in this machine. The frame is so made as to allow cloth of any required width to pass along within it. The horizontal sides support the axis of the several moving parts, and near the centre is an upright part connected at top in which hangs the frame of the flying shear. Near one extremity of this frame rests the beam on which the cloth to be sheared is rolled by means of a crank on the axis of one end thereof, or the same end of the axis is fixed a wheel round which passes a strap that can be tightened or loosened by means of a screw, to oppose resistance enough and stretch the cloth as it passes from the beam to the shear. Being drawn from this beam, the cloth passes between two rollers covered with card teeth, and as these teeth are in a contrary direction to the motion of the cloth, they oppose a uniform & gentle

gentle resistance to its progress, causing it to pass to the shears with a regular motion. A brush hung on springs bears on the progress of the cloth, after it has passed the last mentioned roll, with sufficient force to raise the nap, and prepare it for cutting. Arriving at the shears the cloth passes over what is termed a cushion which bears it up against the motion of the bed shear. This cushion is elevated or depressed by screws so as to elevate the cloth & nap to be cut by the shears according to the kind of cloth to be shear. Having been shear on its progress over this cushion, the cloth is carried to two cylindrical rollers, between which it is drawn forward. In order to effect this object these rollers are made to move in contrary directions and pressed together by means of springs which allow the highest roller to rise and accommodate the space between the rollers to the thickness of the cloth. The rate of the motion of these rollers & the progress of the cloth passing between them is determined by the proportions with their diameters bear to the diameters of the wheels or whills to which they are connected and by which they are moved. The main shaft or principle axis is placed near the centre of the frame and under the shears. It is turned by water, horses, or any proper and convenient force. On the opposite ends of this axis, are two small wheels which by steps or teeth give motion to the larger wheels or whills which turn the cylindrical rollers above mentioned. There is also on one end of this shaft a larger wheel or whill which communicates motion by a strap or band to the crank axis by means of a small wheel at one end thereof. The operation of shearing and the construction of the parts connective therewith I shall not describe. The Bed-shear lies in an horizontal position resting with its ends on the frame, it is fixed by means of screws and having a transverse slot or groove at each end may be advanced to the proper cutting position as the edge of the shear is worn by passing a file or other carding. Care to prevent any vibration in using them

on the shear it may be suspended by means of a hinge or by means of a connecting bar. The flying or moving shear has the edge of its teeth turned and cuts against the bed shear at the advancing point of contact is also in nearly a horizontal position; the end casting, on points which allow the edge of the shear to rise or fall as may be necessary in the act of cutting. To the tail end of this shear is attached a spring which keeps the edge of the flying shear to that of the bed shear at the place of contact during the progress of the cut. besides keeping a regular pressure at the point of contact of the shears. This spring prevents the wear & regulates the stroke to any casual movement in the bed shear.

The flying shear is suspended by bars or in a hanging frame from a connecting bar at the ends of which are points which rest in sliding boxes in the upright exterior frame & may be adjusted by screws and elevate the suspending frame & flying shear to the proper position for cutting against the edge of the bed shear.

This frame & flying shear has an oscillating or pendulum like motion when in the act of cutting, being drawn forward by the bed or arms communicating with the crank axis. In the suspending bar at the point end of the shear there is also a spring which depresses the point of the shear to the proper cutting position after one cut has been made & preparing to the next. The direction of the edge of the flying shear varying from the direction of the edge of the bed shear and forming an angle there with cut in succession from the heel to the point of the shear as the place of contact advances in the same manner as other shears act. The crank axis by means of which the flying shear is drawn forward & comes back in the act of shearing has a small wheel on one end by which it receives motion from the large wheel on the main or principle axis. Two bars or arms extending from the cranks on this axis to the bottom of the suspending bar of the flying shear frame give motion to the flying shear to make the cut. The revolution of this axis

7038

and an equal number of cuts by the shear in proportion to the
of the clock in the passage over the cushion, will depend on the
proportion of the diameter of the large wheel or wheel on the
principle applies to the diameter of the wheel on the crank arm
and by having wheels of different sizes, or increasing their num-
ber, the number of cuts may be adapted to the nature of the work
to be performed.
